UNITED STATES PATENT OFFICE.

JESSE HOPSON AND HENRY HAYWARD PRIEST, OF BRISBANE,
QUEENSLAND, AUSTRALIA.

HAND SIGNAL-LAMP.

SPECIFICATION forming part of Letters Patent No. 732,941, dated July 7, 1903.

Application filed December 26, 1901. Serial No. 87,396. (No model.)

To all whom it may concern:

Be it known that we, JESSE HOPSON, principal messenger Queensland State Legislative Assembly, residing at Bristol street, West End, Brisbane, and HENRY HAYWARD PRIEST, electrical engineer, residing at Overend street, Wooloongabba, Brisbane, in the State of Queensland, Commonwealth of Australia, citizens of Australia, have invented new and useful Improvements in Hand Signal-Lamps; and we do hereby declare the following to be a full, clear, and exact description of the invention, such as will enable others skilled in the art to which it appertains to make and use the same.

Our invention relates to hand signal-lamps used on railways, tramways, &c., and has for its object the construction of simple screen mechanism that can be operated with one hand instead of having to use both hands as with the lamps at present in use.

The invention consists of a light metal cylindrical frame carrying improved red and green screens, said frame being suspended from a spindle in the head of the lamp and capable of being moved through an arc large enough to expose the white, green, or red lights, being so actuated by a small pinion, quadrant, and lever on handle.

In order to clearly illustrate our invention, we will now describe it, reference being made to the accompanying drawings, in which—

Figure 1 is a side sectional elevation of an ordinary hand signal-lamp. Fig. 2 is a part front sectional elevation.

The light metal frame consists of circular ends A A', connected together by three bars B, all of which are grooved to receive the colored screens C, which we make in the following manner: We take sheets of talc or mica of the desired size, and between two of these we place thin sheets of colored gelatin, such as is used by confectioners for bonbons, &c., or other suitable substance. These three sheets may be cemented together or only at the edges. When dry, they may be put in place between the bars B and the ends A A' secured by rivets, solder, or otherwise. The red and green screen so formed is suspended by a metal bow A² from a central post D, fastened to the head of the lamp, while secured to the bow and revoluble on the post D is a small pinion E, into which gears the segmental rack

F, secured to the arbor G, movable in the handle H and end bearing H'. This arbor G is 55 operated by a small lever J, provided with a spring J', working in a three-notched guard, so as to give the three positions, white, red, and green.

The working of the lamp is as follows: When 60 the lever J is in the central notch, the white light is shown, either through a colorless screen or merely through the opening in the frame. On moving the lever J to the right or left with the thumb or finger the screen is 65 moved around and the red or green screen interposed between the light and the lamp-glass, according to its position in the screen.

It will of course be understood that slight variations in the manner of working the 70 screen can readily be made, while a mechanical equivalent may be substituted for the pinion and segmental rack.

Having now particularly described and ascertained the nature of our said invention and 75 in what manner the same is to be performed, we declare that what we claim is—

1. In a signal-lamp a suitable frame carrying different-colored screens, a vertical post suspended from the roof of the lamp upon 80 which said frame is journaled, a gear-wheel rotating upon said post and connected with the frame, a rock-shaft horizontally disposed above the post with means for operating it and a rack of segmental shape carried by said 85 rock-shaft and engaging the gear-wheel, substantially as described.

2. In hand signal-lamps, a light metal frame suspended from a central fixed post in the roof of the lamp, and operated by a pinion, 90 segmental rack on an arbor and a small lever in front of the handle, in combination with colored screens formed by interposing between two thin sheets of talc or mica, colored gelatin or other film cemented together, carried in or secured together by the said light metal frame as herein described.

In testimony that we claim the foregoing as our invention we have signed our names in the presence of two subscribing witnesses. 100

JESSE HOPSON.

HENRY HAYWARD PRIEST.
